UNITED STATES PATENT OFFICE.

FREDERICK G. GRUEN, OF CINCINNATI, OHIO, ASSIGNOR TO THE GRUEN WATCH COMPANY, OF CINCINNATI, OHIO, A CORPORATION OF OHIO.

WINDING MECHANISM FOR WATCHES.

Application filed February 21, 1922. Serial No. 538,313.

To all whom it may concern:

Be it known that I, FREDERICK G. GRUEN, a citizen of the United States of America, and a resident of Cincinnati, in the county 5 of Hamilton and State of Ohio, have invented a new and useful Improvement in Winding Mechanisms for Watches, of which the following is a specification.

My invention relates to winding mechanisms for watches and similar mechanisms.

An object of my invention is to provide a device that will be particularly adapted to withstand repeated windings to which such mechanisms are subjected, without 15 seriously affecting the same, regardless of the small size of the parts employed therein.

Another object of my invention is to relieve the pivot supporting the yoke of a watch from the strain incident to the retention 20 of the yoke in position.

Another object of my invention is to provide a simple device for the purpose stated.

These and other objects are obtained by means described herein and disclosed in the 25 accompanying drawings, in which:

Fig. 1 is a fragmental plan view of a watch showing mechanisms involved in my invention.

Fig. 2 is an enlarged sectional view on line 30 2-2 of Fig. 1.

Fig. 3 is a view similar to Fig. 1, showing the parts in the setting position.

The stem 3 of the watch is mounted upon the plate 4 in any manner common to the 35 art, whereby the stem 3 may be reciprocated longitudinally of itself. Within the plate 4, the stem 3 has revolvably mounted upon it a combined spur and side gear 5, and has a spool 6 splined upon it, the spool 6 having formed at its opposite sides the side gears 7 and 8. The stem 3 has formed in it a groove 9 within which a pin 10 carried by a yoke 11 extends. The yoke 11 is mounted upon the pivot 12, and carries a cam 13 adapted to engage a fork 14 pivotally mounted at 45 15 upon the plate, the bifurcated end 16 of which engages the spool 6 intermediate the gears 7 and 8. The gear 7 is adapted to engage the side gear on the gear 5, and the gear 8 is adapted to engage a gear 17 of a train of gears, through which a shaft 18 carrying the hands of the watch, may be actuated. The plate 4 of the watch has a pocket 19 formed with it, the pocket communicating with a slot 20 extending

through the plate and in which slot 20 is mounted a screw 21, the one end of which has a transverse slot to facilitate rotation thereof, and the other end of which is threaded and engages in a threaded bore 60 22 extending through the yoke 11. A collar 23 is mounted upon the screw 21 and is contained within the pocket 19, the shoulder 24 of the collar and the wall of the pocket 19 serving to limit the movement of the screw 21 toward the yoke. The screw has shoulder 25 formed on it at the upper end of the threaded portion thereof, the shoulder 25 being adapted to engage the yoke 11. The shoulders 24 and 25 are separated 65 at such distance that the yoke will be securely mounted upon the screw 21, yet permitting the screw and yoke to have substantially free movement in relation to the plate. A block 26 is pivotally mounted at 70 75 27 on the plate and has a notched seat 28 into which a lug 29, formed on the yoke, may extend. A spring block 30 is pivotally mounted upon the plate and carries a spring arm 31 which engages the block 26 and 80 85 yieldingly resists movement of the block 26 and the yoke 11. A second spring arm 32 extending from the spring block 30 yieldingly engages the fork 14. Normally the spring arms retain the several parts in such 90 95 relation that the gear 8 will be out of engagement with the gear 17 as shown in Fig. 1. The spur gear is adapted to engage a train of gears adapted to wind the spring of the mechanism as is common in the art 90 and for that reason is not described herein. When the stem 3 is reciprocated longitudinally, the spur gear is disengaged from the spool 6. The fork 14 has a seat 33 formed upon it, which seat the catch 13 95 on the yoke is adapted to engage.

The parts bear such relation when in the position shown in Fig. 1, that normal rotatory motion imparted to stem 3, will be transmitted through the spool and the spur gear to the main spring. When it is desired to set the hands of the watch, the stem 3 is moved upwardly or outwardly of the plate, thereby moving the yoke about the pin 12 and moving the lug 29 on the yoke over the lower wall of the notch in block 26. The movement of the yoke 11 brings the cam 13 into engagement with the fork 14 and moves the fork about its pivotal mounting 15 against the yielding resistance of 110

the spring 32. The movement of the fork, under the influence of the yoke is continued until the cam is lodged upon seat 33. By this time the gear 8 has been moved into engagement with the gear 17. The yielding resistance of the springs 31 and 32 upon block 26 and fork 14 serves to retain the parts in the position shown in Fig. 3. Pressure tending to move the stem inward from the position causes disengagement of the catch from its seat and the parts are returned to their normal positions. The yoke moves about its pivotal mounting, while the pin 21 precludes loosening of the yoke, wherefore the pivotal mounting is relieved from the added function of retaining the yoke in its proper operative relationship to the balance of the mechanism.

What I claim is:

- 20 1. In a device of the class described the combination of a reciprocating stem, a yoke pivotally mounted adjacent the stem adapted to be moved about its pivotal mounting by the reciprocation of the stem, and means fixedly carried by the yoke for precluding movement of the yoke longitudinally of the axis of its pivotal mounting.
- 25 2. In a device of the class described the combination of a slotted plate having a pocket communicating with the slot, a yoke pivotally mounted on the plate, a screw fixedly mounted on the yoke carrying a collar disposed within the pocket for precluding relative lateral movement of the plate and the yoke and for precluding move-

ment of the yoke longitudinally of the axis of its pivotal mounting.

3. In a device of the class described the combination with independent gear trains, of means to selectively actuate the gear trains comprising a yoke, a pivot for the yoke and means fixedly carried by the yoke for precluding movement of the yoke longitudinally of the pivot.

4. In a device of the class described the combination with a pair of plates carrying independent gear trains and a reciprocally mounted stem carrying reciprocating means for selectively actuating the gear trains, the plates having registering bores of substantially equal diameters and one of the plates having formed in it a pocket communicating with the bores and of a diameter in excess of the diameter of the bores, the second plate forming in part a wall for such pocket, of a pivot carried by the second plate, a yoke mounted for oscillation on the pivot having a pivotal mounting on the stem and controlling movement of the reciprocating means carried by the stem, and a stud fixedly carried by the yoke extending into the bores in the plates and carrying a collar located in the pocket and of a diameter in excess of the bores for engagement on the pocket walls and for precluding separation of the yoke and the second plate.

In testimony whereof I have hereunto subscribed my name this 13 day of February, 1922.

FREDERICK G. GRUEN.
